COMBINATION HOLE PUNCH

John T. Schaaff, Washington, D. C., assignor, by mesne assignments, to International Business Machines Corporation, New York, N. Y., a corporation of New York

Application March 26, 1931, Serial No. 525,375

1 Claim. (Cl. 164—113)

This invention relates to record card perforating machines and more particularly to a machine for punching combinations of holes in cards used to control tabulating and sorting machines.

5 In the well-known Peirce system of perforated cards combinations of holes in a given column are used to represent definite information such as numerals or letters of the alphabet. The numerals are ordinarily represented by one or two 10 perforations arranged in four possible perforation positions in the column and the letters of the alphabet are represented by one or more perforations in six positions in the column. Machines for perforating cards according to this 15 system have heretofore been designed along the lines of ordinary typewriting machines and are adapted to punch the necessary combination of holes, one column at a time and at the same time to print the data represented by the holes above 20 the respective columns. In particular instances, it is not necessary to print the character upon the card, the perforations alone being sufficient. For this reason it is possible to employ less costly 25 machines where large numbers of cards are perforated without the corresponding printing. The well known Hollerith type of perforating machine is a very simple device capable of being moved about very readily and is less expensive to construct than other types of punches.

30 I have therefore devised a machine similar in construction to the Hollerith type of perforating machine which is adapted to punch combinations of holes but in which the printing is omitted.

35 In illustrating the invention, I have shown the machine as adapted to punch holes representing numerals and not the alphabet excepting X and R to represent the 11th and 12th positions. I desire to have it understood however that the 40 present disclosure is only illustrative of the invention and that the same idea may be employed by supplying the necessary extra parts to punch combinations representing the entire alphabet as well as the numerals. In the Hollerith type of 45 punch the machine is ordinarily adapted to effect punching in a plurality of columns on the card in which there is a single row of these columns. In the present instance, I have devised 50 means whereby the card may be shifted up and down so that punching may be effected first in one horizontal row of columns and then in a second horizontal row of columns either above or below first row.

55 Referring to the drawings wherein I have shown what I now consider to be the preferred form of my invention:

Fig. 1 is a plan view of the machine with a portion of the cover broken away to show the 60 mechanism contained below;

Fig. 2 is a sectional front elevation taken on line 2—2 of Fig. 1;

Fig. 3 is a sectional elevation taken on line 3—3 of Fig. 2;

Fig. 4 is a detail of the punch actuating mechanism;

Fig. 5 is a detail of the carriage escapement mechanism;

Fig. 6 is a table showing the arrangement of perforations to represent the various numerals 10 or other characters;

Fig. 7 is a modified form of a key connection in which the key may be located to the front of the machine;

Figs. 8 and 8a show the manner in which the 15 top plate of the machine, through which the keys project, may be made;

Figs. 9 and 9a are details of the means for effecting actuation of a plurality of punches.

Referring to the drawings, the frame or base 1 20 of the machine includes a card supporting table 2 and supporting sides 3. The card 4 is carried on the table 2 between upper and lower guide rails 5, 6 and between a right end guide 7 and a left end guide 8 mounted on a carriage 9 which is 25 provided with supporting rollers 10, 11. The rollers are supported on a run or supporting rod 12 and the arm 7a reaches into a guide groove 13 in the bed or card plate 2. A roller 14 mounted on the arm 8 rests upon the card plate. The 30 carriage 9 is provided with rack teeth 15 cooperating with a gear 16 carried in a spring controlled drum 17 mounted in the base of the machine. The spring drum is adapted to be placed under tension when the carriage is moved 35 toward the right and will tend to rotate the gear 16 to move the card carriage back toward the left. Escapement pawls are provided to hold the carriage in any position to which it may be moved and to release it and permit it to move one 40 step to the left whenever a key is actuated to effect the punching of the card. The escapement mechanism includes a pair of pawls 19, 20 cooperating with the ratchet teeth 18 on the carriage. The pawl 19 is loosely mounted on a 45 rod or shaft 21 and is provided with a large hole 22 cooperating with a pin 23 integral with an arm 24 fixed on the shaft. An arm 25 loose on the shaft is connected by a strong spring 26 to an arm 24a which is integral with the arm 24. Also 50 integral with arm 24 is a projection 27 carrying a set screw 28 which cooperates with a projection 25a integral with arm 25. The spring 26 thus tends to rock the arm 25 holding it firmly in engagement with the set screw 28. This arrangement permits a relative setting of arms 24, 25 so that the arm 24 as in effect fixed with respect to the shaft 21.

Counterclockwise rocking of the shaft 21 as viewed in Fig. 5 will thus raise the pin 23 and 60

lift the pawl 19 out of engagement with the ratchet teeth 18. A rearward projection 25b of arm 25 is provided with a pin 29 cooperating in a slot with the pawl 20. Thus when the shaft 21 is rocked counterclockwise to lift the pawl 19 out of the ratchet teeth 18, it will also depress the pawl 20 into cooperation with the ratchet teeth so that when the pawl 19 releases the carriage the latter will still be held by pawl 20 against movement toward the left. The pawl 19 is provided with a projection 19a connected by a spring 30 to the arm 25 so that when the shaft 21 is released and rocked clockwise back to normal position and the pin 23 thus releases the pawl 19 the spring will rock the pawl back into cooperation with the ratchet teeth 18.

A spring 31 cooperating at one end with a fixed portion 32 of the machine presses at its other end against projection 24b of the arm 24 which as we have seen is fixed on the shaft. The spring thus always tends to rock the shaft in a clockwise direction so that when it is rocked in a counterclockwise direction to permit the carriage 9 to escape to the left and is then released it will turn back in a clockwise direction permitting the pawl 19 to reengage the ratchet teeth and lifting the pawl 20 out of engagement. The pawl 19 is not only loosely mounted on the shaft 21 but is sufficiently loose to permit the spring 30 to move it toward the right when it disengages the ratchet teeth 18. When pawl 20 engages the ratchet and pawl 19 disengages, the latter jumps forward slightly to clear the tooth which it has just released. When shaft 21 turns clockwise back to normal position the pawl 19 moves into the next notch and as the pawl 20 releases the ratchet teeth the carriage moves to the left until stopped by pawl 19 with the next column in position for punching. The manner in which the shaft 21 is rocked whenever a key is depressed to effect punching will be brought out presently in connection with the description of the operation of the punches.

The four punches 33 are mounted in upper and lower guides 34, 35 and are pressed upwardly by springs 36. The card 4 is moved between the punch supporting guide 35 and the die plate 37 and is adapted to be perforated by depression of the punch. In order that the punches may be closely spaced apart I provide rather light springs 36. Also the diameter of the punches between the upper head 33a and the lower punching end may be smaller than the diameter of the punching end. The spring 36 is thus weaker than springs that are normally provided to lift the punch out of the card after it has been pressed through and for this reason additional spring pressure may be provided to insure a removal of the punch after it has been released. For this purpose, I provide a plate 38 pivoted at 39 and pressed upwardly by one or more springs 40 against the lower shoulder of the head 33a of each of the punches. Thus, whenever a punch is pressed through the card it not only depresses its spring 36 but also by rocking the plate 38 depresses the additional spring or springs 40. Then when the punch is released spring or springs 40 will aid the spring 36 in lifting the punch out of the card. Resting on the top of each of the punch heads 33a is an interposer bar 41. This bar is pivotally connected at 42 to a bar 43 which is provided with several pin projections 44 adapted to cooperate with cam edges 45 carried by the several operating keys 46. Each key 46 is con-

nected to an arm 47 which is provided with guide rollers 48 cooperating with the side plates of frame 49 of the machine.

A spring 50 is adapted to raise the arm 47 to return the key to its upper or normal position. Each key arm 47 may be provided with one or more of the cam projections 45 as shown in Fig. 3.

Thus where two perforations are used to represent a numeral as in the case of "3" and several others of the numerals the "3" key will have two of the cam projections 45 cooperating with pins 44 of two of the slides 43 to bring about operation of the two proper punches. When the key 46 is depressed its cam or cams 45 will move the proper slide or slides 43 toward the left. This will move the corresponding interposer or interposers 41 to the left over the top of the punch head or heads 33a. These interposers will thus be moved under an operating bar 51 carried by a rocking bail or member 52 pivoted at 53. A spring 54 (see Fig. 4) normally tends to hold the bail 52 in its upper position. Connected to the bail is a link 55 attached at its lower end to an arm 56 pivoted at 57 and fixed with respect to an arm 58 which in turn is connected at its lower end by a link 59 to the armature 60 of an electromagnet 61. The armature is pivoted at 62 and when attracted by the electromagnet operates the parts to effect depression of the bail 52 and operating projection or bar 51. The latter then depresses any of the interposers 41 that have moved to the left, causing them to depress the corresponding punches to effect perforation of the card in the proper places.

Each of the interposers 41 is provided with a notched portion at 63 into which a rocking plate 64 reaches. This plate is pivoted at 65 and is connected at 66 as shown in Fig. 4 to a latch 67. The latch is normally pressed by a spring 68 downwardly and into cooperation with the lower lifting of contact 69. When any key is actuated, moving one or more of the interposers 41 to the left, the latch 67 will thus be raised effecting closure of the contacts 69 to close the circuit through the magnet 61.

The wiring diagram is omitted in the present case as it is of a simple nature and is well known in numerous patents taken out by myself on electrically actuated card perforating machines. When a key is depressed moving one or more of the interposers into position with respect to the punches the magnet 61 is energized causing its armature to rock and causes the punches to be depressed through the card. As the punches are actuated a projection 70 carried by the link 59 is adapted to engage the latch 67 and move it out of cooperation with the contact 69 permitting the latter to open under tension of its leaf spring thus effecting deenergization of the magnet. The magnet actuated parts are then released, permitting them to return to normal position. The armature 60 is connected to toggle links 71 which are connected at the other end 72 to a fixed part of the machine. The toggle permits the armature to move almost into contact with the core of the magnet but does not permit actual physical contact. This avoids unnecessary noise in the operation of the machine.

A projection 73 fixed with respect to the toggle links is provided with a spring 74 which serves to break the toggle as soon as the magnet is de-energized and to cooperate in effect with the spring 54 in restoring the parts to normal position. A spring 75 connected to a projection on each of the interposers 41 will restore the latter

as well as the corresponding slide 43 as soon as the operating key 46 has been released and raised by its spring 50. This will in turn release the rocking plate 64 permitting the latter to be rocked back to its normal position by the spring 68 and this in turn will lower the latch 67 until it snaps back under a lower leaf of contacts 69 ready for the next operation of the machine.

Reaching across under the several interposer bars 41 is a bail 76 loosely mounted on the shaft 21 and having a projection 77 provided with a set screw 78 adapted to cooperate with the arm 24b. Thus when any of the interposer slide bars 41 is depressed it will rock the bail 76 and through the cooperation of the set screw 78 with the arm 24 effect the counterclockwise rocking of shaft 21 to release the carriage, permitting the latter to move one step to the left after the punch is withdrawn to bring the next column on the card into position beneath the punches ready to be perforated upon the next depression of a key.

In order to perforate a series of columns across the card and to then perforate the second series of columns across the card in another field the card guides 5, 6 are adapted to be moved up and down. For this purpose the guides are mounted on links 79, 80 located below the table 2 of the machine. These links are connected by connecting links 81 to arms 82 fixed on shaft 83 which reaches across the inside of the base of the machine and projects outside of the base as in Figs. 1, 2 and has fixed thereon an operating crank 84. Assuming that the upper field of columns is to be perforated first the crank 84 will be turned slightly in a counterclockwise direction moving the guides 5, 6 into their lower position before the punching operation on a particular card is commenced. After the upper field has been completely punched the card carriage is moved back to the left once more and the crank 84 is turned in a clockwise direction moving the guides 5, 6 into their upper position as in Fig. 1. This raises the card so as to present the lower field in position to be punched. The punching operation is then performed in the same manner as in connection with the punching of the upper field. The escapement mechanism operates the same in both instances. After the card has been completely punched it will be removed and a new one inserted and the guides 5, 6 returned to their lower position so that the punching will be done first in the upper field.

When it is desired to pass certain columns upon the card without punching any information in such columns this may be effected by depressing the space key 85. This key is connected to a slide 43 which in turn is connected to an interposer bar 41 resting on the top of a dummy punch 33a. This particular punch is not long enough to penetrate the card but is provided with the usual restoring spring 36. When the key is depressed the interposer 41 moves under the operating bar 51 as usual and the magnet 61 is energized, causing the operating bar to depress the interposer. This causes operation of the escapement mechanism. For each column that is to be skipped the space key will be depressed once.

If it is desired to release the carriage before a complete column across the card has been punched and to permit the carriage to move its full distance to the left thus skipping a number of columns without punching, this may be effected

by depressing the release key 86. This key is adapted to operate a slide 43a which is not connected to any of the interposer bars 41 but is adapted when moved to the left (see Fig. 1) to rock an arm 87 about its pivot 88. The outer end of the arm 87 is shaped as shown in Fig. 5 and rests under a pin 89 fixed in the escapement pawl 19. When the release key is actuated the outer end of this arm moves to the right as viewed in Fig. 5 thus camming the escapement pawl up and out of engagement with the ratchet teeth 18. This raising is permitted by the size of the hole 22 and does not affect the lowering of the pawl 20. Thus the carriage is completely released and is actuated by the spring drum 17 moving the carriage all the way to the left. When the release key is actuated and the pawl 19 is raised the pin 89 rests on the upper level portion of the lever 87 and is held in this position even after the key has been permitted to be restored to its upper position.

When the card carriage reaches the end of its travel to the left the arm 7a strikes a depending bracket 87a fixed to the arm 87 and moves the latter to the left as seen in Fig. 5 back to its normal position, this in turn permits the pawl 19 to drop back into cooperation with the escapement ratchet teeth 18.

As shown in Figs. 8 and 8a, the top plate through which the stems 46a of the keys 46 project, may be made up in sections or strips 46b with cut out sections 46c for the key stems. This obviates the necessity of removing the tops of the keys when assembling the device, so that the tops may be riveted or otherwise secured to the stems.

Fig. 9 shows how several, three in this instance, of the depending cam members 45 may be formed for attachment to one of the keys to effect punching of a corresponding number of holes in a column. As shown in Fig. 9a the several cam members 45 carried by a single key may be offset where desired so that one of them will not interfere with the wrong pin 44.

In Fig. 1 the keys 46 are on the top of the machine. In the modification shown in Fig. 7 the keys 46d are attached to arms 47a integral with the lower portion of arm 47. This will bring the keys down to a convenient location in the front of the machine if desired.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claim.

I claim:

In a machine for perforating in a plurality of columns on a record card, a column of punches corresponding to a single column of the card, and adapted when operated to perforate the card, a plurality of slides, one for each punch, for causing operation of the punches, a plurality of key operated bars each having one or more cam members for actuating the slides to effect operation of one or a combination of several punches, and means actuated in response to a punching operation for feeding the card to present a new column thereof into cooperative relation with the punches.

JOHN T. SCHAAFF.
